UNITED STATES PATENT OFFICE.

PETER H. JACKSON, OF SAN FRANCISCO, CALIFORNIA.

BUILDING-FRONT.

SPECIFICATION forming part of Letters Patent No. 289,105, dated November 27, 1883.

Application filed May 3, 1883. (No model.)

To all whom it may concern:

Be it known that I, PETER H. JACKSON, of San Francisco, State of California, have invented an Improvement in Building-Fronts; 5 and I hereby declare the following to be a full, clear, and exact description thereof.

My invention relates to certain improvements in the construction of fronts of buildings, by which I increase the window-space in the first 10 story for exhibition purposes, as well as permit a greater amount of light from the front to pass to the rear, and do away with the basement piers or columns for supporting the parts between the side walls, and which obstruct 15 the light of the basement.

It consists of a series of suspension rods or columns extending downward from the girder above to the sill, through which they pass or to which they are properly secured, and in 20 connection with them of certain devices and details of construction, all of which will be more fully explained by reference to the accompanying drawings.

Figure 1, Sheet 1, is a view of my invention. 25 Figs. 2 and 3, Sheet 2, are enlarged details of construction. Figs. 4 and 5, Sheet 3, are views of the wrought-iron girder. Fig. 6, Sheet 4, shows manner of supporting the rods. Fig. 7 is a horizontal section of the same with the 30 area-lights.

In the ordinary construction of basements and basement-extensions, it is necessary to employ piers intermediate between the side walls to support the parts above, and these piers 35 not only cut off the light, (which is admitted principally through the basement-extension,) and thus render the rear portion of long basements dark, but also separate the basement from the extension, so that the latter is in the 40 form of a small room and of impaired value. In some cases girders have been placed across this space between the side walls; but as these girders must be of considerable depth to give them the necessary strength, they also cut off 45 considerable light from the rear of the basement.

In my invention, A are suspension-rods, the upper ends of which are secured to the arched or other girder B above, while their lower 50 ends pass through the door sill or plates M and risers N at the bottom, and thus suspend

them from above. The girder B is either an arched or straight girder, having horizontal flanges or shoulders on its upper and lower side, said shoulders or flanges being provided 55 with holes or eyes to receive the attaching rods or bolts of the columns or suspension-bars. In case a curved or arched girder is employed, it is braced by a tie-rod, as indicated at E in Fig. 1. The columns C are 60 bolted or otherwise secured to the girder above, and extend down to the door sills or plates, which are secured to their lower ends.

In Fig. 1 I have shown an arched girder, B, with the column bolted to the solid part of 65 the girder, as at D. (See Fig. 4.) The tops of the columns are grooved out, so as to receive the transverse tie-rods E. (See Fig. 3.)

F shows the method of attachment when a sectional arched girder is used. In this case 70 the column has additional long bolts G, which extend from the flanges of the large columns up through the horizontal bottom flange of the girder, and for a very large column a suspension rod or rods in addition may extend down 75 the length inside the column, with washer-plates and nuts on the bottom of column. These large columns may have the usual doors attached to their backs.

At A, I have shown the suspension-rods extending downward from the girder to which they are secured, and they are partially surrounded by metallic sleeves H, which serve as an exterior finish, and also as sash-bars to hold the glass in place, (see Fig. 7,) thus giving all 85 the necessary strength and support with the smallest possible obstruction for display-windows. These sleeves may be nickel or silver plated, and are swelled or shaped to suit at the top and bottom to form ornamental columns. Filling- 90 in pieces may be fitted into the base and around the rod, and the whole are held together by set-screws. The base will rest upon the door-sill M, while the suspension-rod A passes through a hole in the sill, and also 95 through a collar, O, (see Fig. 6,) which just fits inside the end of the riser, and the whole is thus securely suspended from the rod, suitable bolts and nuts holding the whole in place. The door-sill extends back to the first wood 100 beam P, Figs. 3 and 7, and is screwed down from the top by countersunk screws, which

prevent any side movements. The open-work grating or the solid panel S, Figs. 4 and 7, of the lower part of the window, is secured to the base of the end column C and to the lower part of the sleeve H by bolts, as shown. The illuminated platform T is secured to the bottom of the panel S, while the door-sills M are secured to the sides of the columns, and the riser N is bolted to the front of the column 5 resting on the bottom flange, Q. Where the straight wrought or cast iron girder is employed above, as in Fig. 4, the columns and rods with the sashes are supported from such a girder, and in turn support the door-sills, risers, and bottom plates in the same manner, giving the least possible obstruction to light in the basement, while providing also the fullest space for show-windows, where required. The beam or girder above may be concealed 10 by the cornice and fascia, as shown at R, Fig. 5. With columns suspended in this manner, they being hollow and the bottom left open, with openings under and through the ornamental capitals, a good ventilation of the basement is secured.

Having thus described my invention, what I claim as new, and desire to secure by Letters Patent, is—

1. Suspending-rod depending from a girder 30 above the entrance-openings of a building, said rods being surrounded by recessed metal-

lic sleeves to form sash-bars, substantially as herein described.

2. Suspending-rod depending from beams or girders above the entrance-openings of a building, in combination with the recessed surrounding sleeves with capital and base, as shown, and the panels and illuminating-plate forms secured to and suspended from said rods, substantially as herein described. 35

3. Suspending rods or columns depending from beams or girders above the entrance-openings of a building, and having the surrounding recessed sleeves to form sash-bars, in combination with metallic panels and an illuminating-platform secured to and suspended from said rods without other support from below, substantially as herein described. 40

4. Suspending - columns depending from beams or girders above the entrance-openings 50 of a building, and supporting the door-sills, plates, and panels, as shown, said columns being without support from below and made hollow, with a free communication into the lower ends and out at the upper ends or capitals, so as to ventilate the basement, substantially as herein described.

In witness whereof I hereunto set my hand.

PETER H. JACKSON.
